TOP FASTENER FOR CASEMENT WINDOWS

John Belanger, Los Angeles, Calif.

Application January 31, 1936, Serial No. 61,655

6 Claims. (Cl. 292—95)

This invention has to do in a general way with locking or fastening devices for window closures and the like and is more particularly related to a fastening device adapted for use in securing in closed position the top portion of an outwardly opening casement window of the type shown in United States Letters Patent No. 1,771,073 which was granted to me on July 22nd 1930.

In this type of window construction the windows are hinged to the outside of the window frame and are adapted to open outwardly, the interior of the frame being equipped with a screen. The windows are adapted to be opened and closed through the medium of an operating member secured to the lower edge of the window and working through an opening in the bottom rail of the window screen. Since windows of this character are secured only at their bottom edges, this type of construction has been subjected to some criticism due to the fact that the windows in some instances become slightly warped at their upper edges so that they do not come into the proper closed position and have a tendency to rattle during weather disturbances.

It is, therefore, one object of this invention to produce a fastening device of the class described which is especially adapted for use in locking the top portions of windows of this character in closed position. This fastening device consists in a general way of a plate hook member pivotally mounted in a notch or other suitable aperture provided in the top of the window screen. The plate is provided at one end with a finger adapted to extend over and engage a restraining member mounted on the window and at the other end with an operating handle which projects through the screen rail into the room.

It is one feature of this invention that the operating handle may be equipped with flexible tension members such as cords which can be extended along in front of the top rail of the screen and through suitable supports, such as eyes, secured to the sides of the window frame so as to hang downwardly along the sides of the frame to points where they can be readily reached for actuating the fastening device.

Since the hook plate or fastening device contemplated by this invention must extend through an opening in the closure, it becomes a primary object of this invention to so form this member that the member itself will always act to completely close the aperture through which it works regardless of its angular position. In this way I provide a device which may be operated through the window closure and through which it is im-

possible for insects and the like to enter the room regardless of the position which the hook or plate may assume while the windows are open.

The details in the construction of a preferred form of my invention, together with other objects attending its production will be best understood from the following description of the accompanying drawing which is chosen for illustrative purposes only and in which

Fig. 1 is an inside front elevation of a casement window equipped with a fastening device of the type contemplated by this invention;

Fig. 2 is an enlarged fragmentary sectional elevation taken in a plane represented by the line 2—2 of Fig. 1, and further illustrating details in the construction of a preferred form of fastening device of the type contemplated by this invention;

Fig. 3 is a sectional elevation taken in a plane represented by the line 3—3 of Fig. 2;

Fig. 4 is a plan section taken in a plane represented by the line 4—4 of Fig. 2 and illustrating the fastener in a closed or window locking position;

Fig. 5 is a plan section similar to Fig. 4 but illustrating the plate or hook member as having been swung to a releasing position;

Fig. 6 is a front elevation showing a modified form of the invention; and

Fig. 7 is a sectional view taken along the line 7—7 of Fig. 6.

More particularly describing the invention as herein illustrated, reference numeral 11 indicates a window frame the inside of which is provided with a screen 12. The outside of the window frame 11 is shown as being provided with two casement windows 13 which are hinged at their edges to the frame so as to open outwardly, the actuation of the windows being effected in any suitable manner such as by means of the actuating bars indicated generally by reference numeral 14.

These actuating bars are of the same general construction as was shown and described in my United States Letters Patent referred to above and consist of curved sectional rods which are pivotally attached to the windows and are adapted to slide through clamping blocks 15. These rods are provided with notches 16 adapted to receive lever members 17 for securing the windows in various positions of angular adjustment and are formed in sections pivoted together as indicated at 18 and 18' so that the rod may be swung out of the way when the window is closed, a supporting bracket 19 being provided

for the purpose of holding the rod in such position.

For the purpose of locking the top of the window or outer closure in closed position, I 5 employ a fastening device indicated generally by reference numeral 20. This fastening device consists in a general way of what I may term a bearing member, which in the form of my invention shown in Figs. 1 to 5 inclusive, comprises a block 21 adapted to fit in a notch 22 10 in the upper edge of the top screen rail. The block may be secured in place in any suitable manner such as by means of screws 23 which extend through ears 24 received in a recess 25 15 formed on the upper edge of the notch.

Interposed in the aperture A formed between the bottom of the block 21 and the bottom of the notch 22 in this form of my invention, is an elongated plate member 26 which is pivotally supported at its intermediate portion within the aperture in any suitable manner such as by means of a bearing pin 28 formed on or secured to the plate member and extending into a bearing passage 29 in the block. One end of the plate 26 is shown as being provided with an extending finger 30 which is curved so as to form a hook adapted to extend over a suitable restraining member 31, such restraining member being shown as comprising an angle screw which has one end mounted in the top rail 13' of one of the windows 13. It will be observed from Figs. 4 and 5 that the finger 30 has a cam shaped forward nose 34 and that the pivot pin 28 on the plate 26 is eccentrically positioned with respect to the intermediate portion of the plate member so that the finger has the effect of "reaching out" to extend over the restraining member 31 and draw the top of the window into a tightly closed position in the event it has been slightly warped or sprung.

The inner end of the plate member 26 is provided with what I may term an operating handle 36 which extends inwardly beyond the vertical plane of the inner closure member or screen 45 so that the fastening plate can be readily swung to fastening and unfastening positions.

For the purpose of facilitating the actuation of this fastening plate, I show the operating handle 36 as being equipped with a flexible operating member such as a cord 37 which is secured through an opening 38 in the handle and extends in opposite directions therefrom through eyes or supporting members 40 and 41 secured to the sides of the window frame near the upper edge thereof. The cords 37 may be extended through these supporting members and hang downwardly along the sides of the window frame where they may be concealed from view by drapes or curtains and may be easily reached to actuate the fastening device.

As was pointed out hereinabove, it was the principal object of this invention to provide a fastening device of the class described which is constructed so as to leave no opening through which insects and the like may enter the room when the windows are in open position. With this in mind, my invention contemplates a device which will leave no such opening regardless of the position which the fastening device occupies at any time. This object is accomplished by forming or shaping the intermediate portion of the plate member 26 so that its opposite edges are always in contact with the two sides of the aperture or notch at some point or points for any angular position which the plate member

may assume from either of the extreme positions shown in Figs. 4 and 5. In this form of my invention this is accomplished by forming the two opposite edges of the intermediate portion in the plate member along circular arcs which have a common center in the pivotal axis of the plate member, the radii of such arcs being substantially equal to the distance from such common center to the nearest point of the corresponding side of the aperture or notch. 5 10

In other words, as pointed out above, the pivot pin 28 is eccentrically mounted on the intermediate portion of the plate member so that the distance D to one side of the aperture is substantially greater than the distance D' to the other side. The radius of curvature on the side S of the intermediate portion of the plate member is substantially equal to the distance D and the radius of curvature on the side S' is substantially equal to the distance D' so that in this form of my invention the plate member is always in contact with the sides of the aperture at two points. As was pointed out above the finger 30 is in effect an extension of the side S. Such finger, however, does not necessarily conform with the circular arc along which the side S of the intermediate portion is formed. 15 20 25

It is to be understood of course that the complete closure of the notch by the plate member is not necessarily restricted to the use of circular arcs in the edges of the plate member but may be obtained through the use of cam surfaces on the plate member, also that the sides of the notch may be curved or angularly disposed to cooperate with the plate member in obtaining this effect.

40
In the form of my invention shown in Figs. 6 and 7, the aperture A', within which the plate hook member 26' is contained, is formed within the box member 50 which is mounted in an opening 51 which extends through the top rail 12t of the screen frame. The plate 26', which is identical to the plate member 26 shown in Fig. 4, is secured in the box by a pivot pin 52 and the box is provided with a face flange 53 45 whereby it is secured to the rail 12t by means of screws 54.

It will be observed from the foregoing description that the device contemplated by this invention may be cheaply manufactured and can be easily and quickly installed at any time without the exercise of any great amount of skill. It is also to be understood that while I have described the device as being especially adapted for use in conjunction with outwardly opening casement windows that the device may find various other applications as a fastening device. The invention, therefore is not limited to the precise details in construction nor the precise application described above, but includes within its scope whatever changes fairly come within the spirit of the appended claims.

I claim as my invention:

1. For use in locking window closures embracing inner and outer closure members, the inner member having a notch in one edge, a fastening device comprising a bearing block secured in the top of said notch in spaced relation with the bottom of said notch so as to leave an aperture through said closure; a plate member having its intermediate portion contained in said aperture; pivot means associated with said block and pivotally supporting the intermediate portion of said plate member in said aperture; a hook on 75

one end of said plate member projecting from one side of said aperture.

2. For use in locking window closures embracing inner and outer closure members, the inner member having a notch in one edge, a fastening device comprising a bearing block secured in the top of said notch in spaced relation with the bottom of said notch so as to leave an aperture therebetween; a plate member having its intermediate portion contained in said aperture; pivot means associated with said block and pivotally supporting the intermediate portion of said plate member in said aperture; a hook on one end of said plate member projecting from one side of said aperture; and an operating handle on said plate member projecting from the other side of said aperture, the intermediate portion of said plate member being shaped so that the opposite edges thereof are at all times in substantial engagement with the sides of said aperture.

3. For use in locking window closures embracing inner and outer closure members, the inner member having a notch in one edge, a fastening device comprising a bearing block secured in the top of said notch in spaced relation with the bottom of said notch so as to leave an aperture therebetween; a plate member having its intermediate portion contained in said aperture; pivot means associated with said block and pivotally supporting the intermediate portion of said plate member in said aperture; a hook on one end of said plate member projecting from one side of said aperture; and an operating handle on said plate member projecting from the other side of said aperture, the intermediate portion of said plate being shaped so that its opposite edges are in the form of circular arcs having a common center in the pivotal axis of said plate and having radii equal respectively to the distances from said pivotal axis to the nearest point of the respective edges of said aperture.

4. For use in locking window closures embracing inner and outer closure members, the inner member having a notch in one edge, a fastening device comprising a bearing block secured in the top of said notch in spaced relation with the bottom of said notch thereby forming an aperture through said closure; a plate member having its intermediate portion contained in said aperture; pivot means associated with said block and pivotally supporting the intermediate portion of said plate member in said aperture; a hook on one end of said plate member project-

ing from one side of said aperture; and an operating handle on said plate member projecting from the other side of said aperture the intermediate portion of said plate being shaped so that its opposite edges are in the form of circular arcs having a common center in the pivotal axis of said plate and having radii equal respectively to the distances from said pivotal axis to the nearest point of the respective edges of said aperture, the radius of one of said curves being substantially greater than the radius of the other curve.

5. For use in locking window closures embracing inner and outer closure members, the inner member having a notch in one edge, a fastening device comprising a bearing block secured in the top of said notch; a plate member having its intermediate portion interposed between the bottom of said bearing block and the bottom of said notch; pivot means associated with said block and pivotally supporting the intermediate portion of said plate member in said notch; a hook on one end of said plate member projecting from one side of said notch; and an operating handle on said plate member projecting from the other side of said notch, the intermediate portion of said plate being shaped so that its opposite edges are in the form of circular arcs having a common center in the pivotal axis of said plate and having radii equal respectively to the distances from said pivotal axis to the nearest point of the respective edges of said notch, the radius of one of said curves being substantially greater than the radius of the other curve and said hook being a continuation of the edge of said plate having the greatest radius of curvature.

6. For use in locking window closures having a fastener member receiving opening therein: a fastener member pivotally mounted within the opening in the window closure, said fastener member comprising an intermediate portion forming a closure for the opening in the window closure, an eccentric hook on said plate member projecting from one side of the opening in the window closure and a handle on said plate member projecting from the other side of the opening in said window closure, said intermediate portion having opposite edges extending to the sides of the opening in said window closure, said edges being formed on two arcs having as a common center the pivotal axis of said member, but having different radii.

JOHN BELANGER.
